Primary Examiner — Robert M. Spear

(57) **CLAIM**

The ornamental design for a wake up light, as shown and described.

DESCRIPTION

1.1 is a front perspective view of a first embodiment of a wake up light showing our new design;
 1.2 is a front elevational view thereof;
 1.3 is a rear elevational view thereof;
 1.4 is a right side elevational view thereof;
 1.5 is a left side elevational view thereof;
 1.6 is a top plan view thereof; and
 1.7 is a bottom plan view thereof;
 2.1 is a front perspective view of a second embodiment of a wake up light showing our new design;
 2.2 is a front elevational view thereof;
 2.3 is a rear elevational view thereof;
 2.4 is a right side elevational view thereof;
 2.5 is a left side elevational view thereof;
 2.6 is a top plan view thereof; and
 2.7 is a bottom plan view thereof.
